UNITED STATES PATENT OFFICE.

HARVEY GODFREY, OF NEWPORT, KENTUCKY.

AUTOMATIC GAS CUT-OFF.

Application filed June 1, 1925. Serial No. 34,048.

To all whom it may concern:

Be it known that I, HARVEY GODFREY, a citizen of the United States, residing at Newport, in the county of Campbell and State of Kentucky, have invented certain new and useful Improvements in Automatic Gas Cut-Offs, of which the following is a specification.

This invention relates to device for controlling the supply of gas, to automatically shut off the flow in event of the pressure being reduced from any cause to a degree sufficient to extinguish the flame of the burners, and thus prevent the flow of gas through unlighted burners when the pressure is resumed, and has for one of its objects to improve and simplify the construction and increase the utility and efficiency of devices of this character.

With these and other objects in view, the invention consists in certain novel features of construction as hereinafter shown and described and then specifically pointed out in the claims, and in the drawings illustrative of the preferred embodiment of the invention.

Fig. 1 is a side elevation of the improved device applied to a conventional gas heater, with the parts arranged to permit the flow of gas through the supply conductor.

Fig. 2 is an elevation on an enlarged scale, and partly in section, illustrating the operation.

Fig. 3 is a detail in section on the line 3—3 of Fig. 2.

Fig. 4 is a detail in section on the line 4—4 of Fig. 2.

Fig. 5 represents portions of the tripping mechanism in perspective.

The improved device may be associated with any of the various makes of gas heating or cooking apparatus, and it is not desired to limit the device in any manner in this respect, but for the purpose of illustration the device is shown arranged in connection with a conventional gas heater in which the supply conductor is indicated at 10, having a controlling valve at 11 and a plurality of burners at 12.

The improved device includes a suitable support, preferably in the form of a casing having a bottom or floor portion 13, back 14, and ends 15, the bottom portion 13, resting upon the heater frame 16 adjacent the

burners 12 and in position to receive the heat radiated therefrom.

Pivoted to swing at 17 relative to the back 14 of the casing is a supporting plate 18 having spaced stops 19 coacting with a pin 20 extending from the casing to limit the throw or movement of the plate on its pivot. At its opposite end the plate 18 is reduced as shown at 21.

Attached to the plate 18 as by straps 22 is a curved tubular container 23 enlarged at one end as at 24, to contain an element capable of expansion by heat, such as mercury, alcohol, or the like. The member 23 is so located that its center line is beneath the pivot 17, so that when the medium within the tube and its bulb 24 is expanded by heat, the major portion will pass to the right hand end of the tube and overcome the gravity of the plate 18 and depress the reduced end 21, and dispose the plate in the position shown in full lines in Fig. 2 with the lower projection 19 against the pin 20.

The member 23 is thus a thermostatic element.

When the heat is reduced the medium within the tube will contract and dispose the major portion of the medium at the other side of the line of the pivot 17, and dispose the plate 18 and its tube 23 in the position shown in full lines in Figure 1 and in dotted lines in Figure 2, with the upper projection 19 against the pin 20.

Attached at 25 to the rear wall 14 of the casing, is a bracket 26 having a pivot pin 27 extending therefrom, and mounted to swing upon the pin 27 is a trip plate 28 having a longitudinally directed toe element 29.

Pivoted intermediate the ends at 30 to the trip plate 28 is a trip finger having a downwardly inclined portion 31 of greater weight than the remaining portion 32, to hold the latter normally against a stop pin 33 extending from the trip plate 28.

Another stop pin 34 extends from the member 26 and spaced from the pin 33, to limit the downward movement of the trip plate 28. The portion 32 of the trip finger extends into the path of the portion 21 of the plate 18, so that as the latter is tilted on its pivot 17 by operation of the thermostat device, the terminal 21 will swing the trip finger on its pivot and pass beneath it, but without effecting the trip plate 28,

but at the return movement of the plate 18 caused by the reduction of the temperature, the point 21 will pick up the trip finger and swing it against the stop pin 23 and actuate the trip plate 28, as hereafter explained.

Pivoted at 35 to the wall 14 of the casing, is a lever arm 36, and pivoted at 37 to the arm 36 is a stop latch 38 having a weighted end 39.

10 The terminal of the member 38 is provided with a bearing roller 40 in position to simultaneously engage the inclined face of the nose portion 29 of the member 28 and the inclined face of a projection 45 on the bracket 26.

15 The operating arm 41 of the controlling valve 11 is provided with a weight 42, and is coupled to the lever arm 36 by a rod 43. A lifting ring 44 is attached to the lever 20 arm 36.

25 With an apparatus thus constructed and installed, the lever arm 36 is elevated first manually by the lifting ring 44 to open the valve 11 to permit the flow of gas to the 30 burners 12, and the burners lighted. This movement of the arm 36 causes the swinging stop latch 38—39 to pass over both of the nose portions 29 and 45 of the plate 18 and bracket 26, and assume the position shown in full lines in Figures 1 and 2.

35 When the heat from the burners expands the element within the tube 23, the plate 18 is tilted on its pivot 17 as before described and causes the reduced terminals 21 to be depressed into the position shown in full lines in Figure 2, this movement causing the point 21 to swing the trip finger 32—31 on its pivot, but without effecting the trip 40 plate 28.

45 The supporting plate 18 will retain the position shown in full lines in Figure 2 so long as the burners are lighted and radiate sufficient heat to maintain the element within the tube 23 expanded.

50 When the burners are turned off, the cooling of the element within the tube 23 will cause it to contract and move the center of gravity to the other side of the pivot 17 and tilt the plate 18 and elevate the reduced portion 21 and cause it to engage the end 32 of the trip finger and cause the latter in turn to engage the pin 33 and swing the trip plate 28 on its pivot 27 and depress the nose portion 29 and cause the end of the trip plate 28 to engage the roller 40 and detach the latch element 38—39 from engagement with the nose portion 45 of the bracket 26, and thus release the lever arm 36 and correspondingly release the weighted valve lever 60 41 and permit the latter to close the valve 11, and cut off the flow. This automatic action takes place when the flow to the burners is cut off either, manually or accidentally.

65 The improved device is primarily intended

to automatically cut off the supply of gas to the burners in event of the flow being interrupted from any cause so that when the pressure is restored, the gas will not reach the burners and pass therethrough without 70 being lighted.

By this simple arrangement the escape of gas through open unlighted gas burners or jets is effectually and automatically prevented whether such escape is due to wind, 75 interruption of the gas pressure, overflow from cooking vessels, carelessness, or any other causes.

The preferred embodiment of the invention is disclosed in the drawings and set forth 80 in the specification, but it will be understood that modifications within the scope of the claimed invention may be made in the construction without departing from the principle of the invention or sacrificing any of 85 its advantages.

Having thus described my invention what I claim is:

1. In an automatic cut off for gas burners, a controlling valve in the supply conductor 90 adapted to be closed by a weighted lever, a poised supporting member, a thermostatic device coupled to said poised member and operative to control the movement thereof by change of temperature, a swinging arm 95 connected to the weighted valve lever, a movable trip latch carried by said swinging arm, a stationary inclined stop 45 engaged by said trip latch to hold said swinging lever arm in position to hold the valve open, a swinging trip plate having a vertical terminal normally engaging the trip latch, and a trip finger swinging upon the trip plate and limited in its movement in one direction and extending into the path of the 105 poised supporting plate.

2. A device of the class described, comprising a support adapted to be disposed within the influence of heat radiated from gas burners, a supporting plate pivoted intermediate the ends relative to said support, a thermostatic device attached to said poised member and operative to control the movement thereof by the heat from said burners, a lever arm swinging at one end 110 upon said support, a weight controlled valve in the gas conductor of said burners, connecting means between the lever arm and the weighted valve controlling means, and means whereby reduction of the temperature 115 caused by the interrupted flow to said burners will cause the thermostatic device to close said valve.

3. A device of the class described comprising a stationary support, a supporting plate pivoted intermediate the ends relative to said stationary support, a tubular member attached to said supporting plate and extending at each side of the pivot 125 thereof, said tubular member containing an 130

element expansible by heat and operative to swing the supporting plate by expansion and contraction of said element, a conductor for gas, a controlling valve in said conductor, yieldable means for closing said valve, means for holding said valve controlling means in open position, and means operative by the contraction of said expansible element to release said valve closing means.

4. A device of the class described comprising a supporting plate pivoted intermediate the ends, a tubular member attached to said supporting plate and extending at each side of the pivot thereof, said tubular member containing an element expansible by heat and operative to swing the supporting plate by the expansion and contraction of said element, a conductor for gas, a controlling valve in said conductor, yieldable means for closing said valve, means for holding said controlling means in open position, and means operative by the contraction of said expansible element to release said valve closing means.

5. A device of the class described comprising a supporting plate pivoted intermediate the ends, a tubular member attached to said supporting plate and extending at each side of the pivot thereof, said tubular member containing an element expansible by heat and operative to swing the supporting plate by the expansion and contraction of said element, a conductor for gas, a controlling valve in said conductor, yieldable means for closing said valve, a swinging lever arm coupled to said valve controlling means, a trip latch swinging on said lever arm, a stationary bracket device having a portion operative to engage said holding latch and retain said valve control in open position to disengage the trip latch from the bracket projection, and a trip finger movable upon said trip plate and extending into the path of said pivoted supporting plate.

In testimony whereof, I affix my signature hereto.

HARVEY GODFREY.
